UNITED STATES PATENT OFFICE.

CHAUNCEY E. FRAZIER, OF WASHINGTON, PENNSYLVANIA.

DECORATING OR ANNEALING OVEN.

1,389,583.

Specification of Letters Patent.

Patented Sept. 6, 1921.

Application filed March 26, 1921. Serial No. 455,719.

To all whom it may concern:

Be it known that I, CHAUNCEY, E. FRAZIER, a citizen of the United States of America, and resident of Washington, county of Washington, and State of Pennsylvania, have invented certain new and useful Improvements in Decorating or Annealing Ovens, of which the following is a specification.

10 This invention relates broadly to decorating furnaces, and more specifically to a furnace or oven of the muffle type designed for burning or fixing decorations on articles of glassware, ceramic ware and enamel ware, 15 and also adapted for annealing purposes.

The primary object of the invention is to produce a muffle oven which has a construction and arrangement providing for the firing or decorated ware for fixing the pig- 20 ments or other substance employed in the decoration, for annealing or re-annealing of glass, steel, or the like, and which affords means whereby may be controlled the temperature to which the ware is subjected, the 25 rate at which the ware is heated to the maximum temperature, and the rate at which the ware is cooled following heating to the maximum or following a predetermined reduction in the temperature.

30 With these and other important objects in view, the invention resides in the features of construction, arrangement of parts and combinations of elements which will herein- after be fully described, reference being had

35 to the accompanying drawings, in which— Figures 1 and 1^a illustrate the invention in longitudinal section taken substantially on the line 1—1, Fig. 3;

40 Figs. 2 and 2^a show a section on line 2—2, Fig. 3; and Fig. 3 is an enlarged transverse section on line 3—3, Fig. 1.

Referring to said drawings, 1 indicates generally the muffle chamber to the front 45 end of which leads an inclosed passage or entrance way 2 and from which leads a similar passage or exit way 3, an endless carrier consisting of sprocket chains 4 with trans- 50 verse carrier bars 5 being provided for sup-

porting the usual ware-carrying pans and having its upper traverse arranged for continuous travel through said chamber and said passages. As shown, said carrier includes supporting rollers 6 which travel 55 upon trackways 7 mounted on the floor 8 of said chamber and upon transverse beams 9

in said passages. Sprocket wheels 10 and 11 located at the entrance and exit ends of the oven passages carry the chains 4 and are adapted to be propelled in any appropriate 60 manner for advancing the latter.

The floor 8 and roof 12 of the muffle chamber 1 are formed of thin slabs or plates of refractory tile or other suitable material which are adapted to permit of radiation of 65 heat therethrough to the muffle chamber with a minimum of waste. Located in the side walls of said muffle chamber at spaced intervals are thin panels 13 of similar mate- 70 rial, also designed to permit of maximum ra- diation of heat therethrough.

The plates or tiles 8^a of the floor 8 are mounted upon brick-work supports 14 which are arranged in spaced relation to provide therebetween longitudinally extending un- 75 der-floor flues 15 which are separated from the return passage 16 provided for the carrier by interengaged slabs 17 supported in a suitable manner, as by transverse I-beams 18 having their ends set in the outer furnace 80 walls 19.

The side walls of the muffle chamber are located at a suitably spaced distance from the outer furnace walls 19, and the latter are surmounted by an arch-like crown 20 85 between which and the roof or top 13 of said chamber is a plurality of longitudinally alined chambers, herein shown as four in number and designated 21, 22, 23 and 24, 90 which are separated by walls or partitions 25. The chambers 22 and 23 are primary combustion chambers or fire boxes to which fuel, as natural gas, producer gas, or fuel oil, is introduced through burner openings 26 provided in the crown 20. The opposite 95 outer, or end, chambers 21 and 24 are sec- ondary combustion chambers which receive the products of combustion from the fire- boxes 22 and 23 in a manner which will here- inafter be described and which discharge 100 such products, as through ports 27, to suit- ably located stacks 28.

The space intermediate the side-walls of the muffle chamber 1 and the furnace walls 19 is divided by relatively spaced webs 33 105 into vertical flues 29 which communicate at their upper ends with the muffle overlying chambers and at their lower ends with short horizontal transversely directed flues or pas- 110 sages 30 leading to the under-floor flues 15 directly over the level of the slabs 17. Said vertical flues 29 are located directly adja-

cent to the panels 13 in the side walls of the muffle chamber so that a part of the heat passing through said flues is absorbed and directly radiated into said chamber by 5 said panels. Dampers 31 movable into or across said vertical flues 29 provide means whereby the passage of heat through the latter, particularly those communicating with the secondary chambers 21 and 24, may be 10 controlled or completely cut off.

Heat generated in the primary fire-boxes 22 and 23 passes downward through the vertical side flues 29, thence through the passages 30 to the longitudinal under-floor flues 15, whence it passes outward and upward through similar passages 30 and flues 15, respectively, to the secondary chambers 21 and 24, and thence to the stacks 28 through the ports 27. It will thus be seen that the muffle 20 chamber 1 is almost completely surrounded by the heat which courses through the various flues and passages, and that, consequently, there is a substantially uniform radiation of heat into said chamber from all 25 directions, resulting in an even heat distribution, which is particularly advantageous in an oven of this character in that the ware acted upon is uniformly heated throughout and is not subjected to the unequal strains 30 which would be imposed thereon were certain of the muffle chamber walls permitted to remain relatively cool. Stated somewhat differently, due to the arrangement of the muffle chamber in such manner that each of 35 its walls receives and radiates heat to the interior thereof, not only is an efficient and economical heat distribution effected, but the effective treatment of the ware is promoted.

40 In practice, any treatment of the ware best suited to the particular character of its decorations is readily effected; that is to say, the oven may be operated to secure any desired temperature range in its different 45 parts and to provide any required temperature curve. For instance, if it be required that the ware, which is cold when it enters the front end of the oven, shall be heated gradually to a maximum temperature and 50 then maintained at said maximum throughout an interval of time followed by gradual cooling, either one or both of the primary combustion chambers 22 and 23 may be fired, according as it is desired that said 55 maximum be comparatively low or high, and the dampers 31 of the vertical flues 29 communicating with the opposite secondary chambers 21 and 24 will be allowed to remain open to allow free communication 60 with the latter. Should it be desired that the ware be subjected to a flash heat—that is, subjected to the maximum temperature for a comparatively short interval—the dampers of the vertical flues communicating 65 with the secondary chamber 24 should

be closed, as may also the dampers of the vertical flues which communicate with the primary combustion chamber 23, provided the maximum temperature required is obtainable by the firing of the single primary 70 chamber 22. If a somewhat higher flash-heat temperature be required, a low fire may be maintained in primary chamber 22 and the maximum provided in primary chamber 23, with the dampers of the flues 75 leading to secondary chamber 24 closed or partially so. Further, it will be apparent that various other results are readily obtainable through manipulation of the dampers of the various chambers. In brief, 80 it will be understood that the described construction and arrangement of the parts of the oven provides for such absolute control of heat that the production of any temperature curve which may be desired, or which 85 may be best suited to the character of ware and decorations under treatment, is readily obtainable.

Sight openings, or port holes 32 are provided in the walls 19 at suitable intervals, 90 through which may be observed the character and effects of the fire upon the articles passing through oven.

What is claimed is—

1. In a muffle oven, a furnace comprising 95 a primary combustion chamber and secondary chambers located at opposite ends of said primary chamber, means separating said chambers, a muffle extending through said furnace beneath said chambers and comprising a floor, side-walls and a roof, vertical flues formed between the side-walls of said muffle and those of the furnace, and flues extending longitudinally beneath said floor and having communication with said vertical flues, said communicating flues constituting 100 passages around the muffle for conducting products of combustion to said secondary chambers.

2. In a muffle oven, a furnace comprising 110 a primary combustion chamber and secondary chambers located at opposite ends of said primary chamber, means separating said chambers, a muffle extending through said furnace beneath said chambers and comprising a floor, side-walls and a roof, vertical flues formed between the side-walls of said muffle and those of the furnace, flues extending longitudinally beneath said floor and having communication with said vertical 115 flues, said communicating flues constituting 120 passages around the muffle for conducting products of combustion to said secondary chambers, and means operable into and out of closing relation to said passages for controlling the temperature imparted to said muffle at any point in the length of the latter.

3. In a muffle oven, a furnace comprising 125 a primary combustion chamber and secondary chambers located at opposite ends 130

of said primary chamber, means separating said chambers, stacks with which said end chambers communicate, a muffle extending through said furnace beneath said chambers, flues extending longitudinally beneath said muffle, vertical flues between said muffle and the side-walls of the furnace affording communication between the longitudinal flues and the various chambers, and adjustable means for controlling the passage of heat through said flues and whereby the temperature of the muffle at any part of its length may be regulated.

4. In a muffle oven, a furnace comprising a plurality of longitudinally aligned primary combustion chambers, and secondary combustion chambers located at opposite ends of said primary chambers, division walls separating said chambers, a muffle extending through said furnace beneath said chambers, flues extending longitudinally beneath the floor of said muffle, vertical flues between said muffle and the sides of the furnace, said vertical flues affording communication between said underfloor flues and each of the various chambers whereby heat from said primary chambers may be conducted around said muffle to the secondary chambers, and means operable into and out of closing relation to said vertical flues whereby the passage of heat through any of the latter may be controlled.

5. In a muffle oven, a furnace comprising a plurality of longitudinally aligned primary combustion chambers, and secondary combustion chambers located at opposite ends of said primary chambers, means preventing direct communication between said chambers, stacks in communication with said secondary chambers, a muffle extending through said furnace beneath said chambers,

flues located beneath said muffle, flues between said muffle and the side walls of said furnace and providing means of communication between said under-floor flues and the various chambers, said side flues and under-floor flues constituting muffle-surrounding courses traversed by products of combustion in passing from the primary combustion chambers to the secondary chambers, and adjustable means in said flues for controlling the passage of said products.

6. In a muffle oven, a furnace comprising a plurality of longitudinally aligned primary combustion chambers, and secondary combustion chambers located at opposite ends of said primary chambers, means preventing direct communication between said chambers, stacks in communication with said secondary chambers, a muffle extending through said furnace beneath said chambers, flues located beneath said muffle, flues between said muffle and the side walls of said furnace and providing means of communication between said under-floor flues and the various chambers, said side flues and under-floor flues constituting muffle-surrounding courses traversed by products of combustion in passing from the primary combustion chambers to the secondary chambers, adjustable means in said flues for controlling the passage of said products, inclosed ways located at opposite ends of and in alinement with the chamber of said muffle, and ware carriers movable through said ways and said muffle chamber.

In testimony whereof, I affix my signature in presence of two subscribing witnesses.

CHAUNCEY E. FRAZIER.
